METHOD OF MANUFACTURING TUBES

George E. Barnhart, Pasadena, Calif.

Application March 8, 1943, Serial No. 478,456

4 Claims. (Cl. 29—156)

This invention relates to a method for manufacturing tubes.

The general object of the invention is to provide an improved method whereby tubes may be operated upon to vary the diameter and/or wall thickness of different portions of the tube.

A more specific object of the invention is to provide a novel method for making a tube by means of which the tube may be provided with thickened wall portions which may be arranged at the ends of the tube.

A further object of my invention is to provide a novel method of working a tube so that the grain structure of the tube is improved.

Other objects and advantages of the invention will be apparent from the following description taken in connection with the accompanying drawings, wherein:

Fig. 1 is a side elevation, with parts in section, showing my improved apparatus;

Fig. 2 is a view similar to Fig. 1 showing the parts in another position;

Fig. 3 is a central sectional view through a tube from which my improved tube is made;

Fig. 4 is a central sectional view showing die members with the tube therein and with one end of the tube expanded and with a headed member in position for movement;

Fig. 5 is a view similar to Fig. 4 after the headed member has passed through the intermediate portion of the tube;

Fig. 6 is a view similar to Fig. 4 showing the tube reversed and being pulled through the die to reduce the external diameter and to thicken the wall portion of one end portion of the tube, and

Fig. 7 is a view similar to Fig. 4 showing the other end of the tube reduced in diameter and its wall thickened.

Referring to the drawings by reference characters I have shown my invention as embodied in a tube working apparatus which is indicated generally at 10. The apparatus includes a frame 11 held in place by supports 12. The frame 11 includes an upper member 13, end members 14 and a bottom member 15.

On the bottom member 15 I arrange the lower half 16 of a die which is held in place by fastening members 17. Rods 18 are mounted to slide through apertures in the bottom member 15 and at their top are connected by a plate 19 on which the upper half 20 of the die is held in place by fastening members 21. The upper end of a spring 22 engages a support 22a while the lower end of the spring engages a pin 22b which passes through

an aperture in the member 13 and is secured to the upper plate 19 and normally holds the plate 19 and the die portion 20 in elevated position above the die portion 16. The rods 18 below the lower member 15 are connected by a plate 23 to which a plunger rod 24 is connected.

The plunger rod 24 has a piston 25 thereon, which is disposed in a cylinder 26. The cylinder 26 is preferably operated by hydraulic means (not shown) and the construction is such that by causing the piston 25 to move downwardly in the cylinder 26 the die 20 will be brought down into engagement with the die 16. When the piston 25 is released the spring 22 will return the die to its upper position.

In the practice of my invention I take a tube 38 which may be made of aluminum, steel, copper or other suitable material. This tube preferably has a substantially uniform wall thickness and is preferably of substantially uniform diameter throughout. The tube may be of any suitable length.

The die members 16 and 20 together form a cavity indicated generally at 31. This cavity includes an intermediate portion 32 which is cylindrical and the diameter of which is slightly greater than the exterior diameter of the tube 38, so that a small annular space 33 is provided between the exterior of the tube and the adjacent die wall. At its front end the die cavity 31 includes cylindrical portions 34 and 35. The portion 34 is connected with the portion 32 by a frusto-conical portion 36 and the portions 34 and 35 are connected by a frusto-conical portion 37.

At its rear end the cavity 31 includes a cylindrical portion 38 connected to the portion 32 by a frusto-conical portion 39.

According to the disclosure, the first step in the manufacture of the tube consists of inserting a mandrel 50 (Figs. 1 and 2) into one end of a tube in the die. The mandrel includes portions 51 and 52 which correspond to the die portions 34 and 38. The mandrel also includes a tip 53 which is of substantially the same diameter as the internal diameter of the tube 38.

The mandrel 50 is mounted on a piston rod 54 which works in the cylinder 55. The cylinder 55 includes a partition 56 and the piston rod 54 includes a head 57 which reciprocates in the cylinder due to action of hydraulic fluid in the cylinder 55 controlled by means not shown.

The cylinder 55 is mounted on parallel links 58 so that it may move from the dotted line position shown in Fig. 1 to the full line position shown in this figure. The links 58 are moved by means of

a piston rod 61 having an end portion working in a slot 62 in one of the links 60. The piston rod 61 includes a head 63 arranged in a cylinder 64 and it is operated hydraulically by means not shown.

In operation the piston 63 is actuated to raise the cylinder 51 to its upper position whereupon the piston 71 is operated to force the mandrel 50 into the tube 30. These actions occur after the piston 25 has been actuated to cause the die members to move together to the position shown in Fig. 4.

To prevent the tube 30 from being forced from the die by the mandrel 50, I provide a stop member 70 which is mounted on a piston 71 in a cylinder 72 which is supported by links 73. When the piston 71 is in the forward position, as shown by solid lines in Fig. 1, the stop member 70 engages the inner end of the tube 30 and holds the tube in place.

The cylinder 72 is moved to inoperative position by a piston rod 74 the free end of which works in a slot 75 in one of the arms 73. The piston rod 74 has a head 76, which reciprocates in a cylinder 77. When the piston 76 is in its retracted position, as shown in full lines in Fig. 2, the cylinder 72 is raised to an inoperative position.

After the mandrel 50 has formed one end of the tube into the shape shown in Fig. 4 the mandrel is withdrawn. The tube 30 is preferably of such length that the end 80 thereof is disposed adjacent to the portion 38 and thus end 80 is not shifted axially during the step produced by the mandrel 50.

After the mandrel is removed and the cylinder 55 is lowered, I lower a cylinder 85 which is supported by parallel links 86 into position. This is done by means of a piston rod 87 which has an end portion working in a slot 88 in one of the arms 86. The rod 87 has a piston 89 thereon which works in a cylinder 90. The piston rod 87 is continued at 91 and has an end portion which works in a slot 92 in a pivoted arm 93. The arm 93 supports a flanged roller 94 and the construction is such that the links 86 and 90 will move from the solid line position in Fig. 2 to the dotted line position in this figure when the piston 89 is actuated. The cylinder 85 has a piston 95 therein which is connected to a rod 96. The rod 96 has a clutch member 97 thereon, the details of which form no part of this present invention. The clutch member 97 releasably engages a head 98 of a come-along rod 99 which has a head 100 thereon. The come-along rod 99 is supported by the roller 94 previously described. The flanges of the roller 94, when the parts are in the position shown in Fig. 1, straddles the cylinder 55.

When the parts are in the position shown in Fig. 2 and the piston 85 moves forward in its cylinder 85, the rod 86 will advance, pushing the come-along rod 99 through the tube in the die, whereupon the grip portion 101 on the forward end of the come-along will be engaged by a clutch member 102 on a come-along 103. The come-along is mounted on ways 104 so that it may be moved from the position shown in Fig. 1 to the position shown in Fig. 2. The details of construction of the come-along form no part of the present invention.

After the clutch member 102 engages the rod portion 101 the come-along is operated thus pulling the head member 100 through the tube. The diameter of the member 100 plus twice the wall thickness of the tube 30 is slightly greater than

the interior of the portion 32 of the die, so that as the head member moves through the tube the adjacent portion of the tube wall is forced outwardly and is thinned. At the same time the end 80 of the tube is caused to advance along the inside of the die. The fact that the space 33 is provided permits this action to occur smoothly.

There is no scraping of the tube along the inner face of the die and the drawing method described results in an improved grain. As the end 80 advances the material adjacent thereto moves outwardly and into engagement with the portions 38 and 39 of the die so that the end of the tube 30 assumes the position shown in Fig. 5. The above described steps provide a tube having enlarged stepped end portions and a cylindrical intermediate portion.

The die parts are then separated and the tube 30 removed. The end of the tube formed by the largest portion of the mandrel 50 is then chamfered as at 110, Fig. 6, as by spinning, and a pull member 111 is run through the tube. The pull member has a head 112 which engages the chamfered portion and at the end remote from the head has a head portion 113. The tube is then placed in the die with the end 80 of the tube directed towards the portion 39 of the die and the die is closed.

30 The head 113 is then engaged by the clutch member 97 and the piston 85 is operated to pull the pull member 111 through the die. As the rod moves the tube is pushed through the die along with the rod. The end portion 80 of the tube first engages the conical portion 39 of the die and as the tube advances its diameter is decreased as it passes through the die. This action continues with the portions of the tube formed by the die parts 38, 34, 37 and 35, in the order 35 named, engaging the part 39 of the die and having their respective diameters reduced. As a result the larger end of the tube previously formed by the mandrel is reduced in diameter as shown at 114, Fig. 7.

45 The steps described produce a tube having an intermediate portion of uniform wall thickness and having end portions of greater wall thickness than the intermediate portion and with the exterior diameter of the tube uniform throughout.

50 From the foregoing description it will be apparent that I have invented a novel method for making tubes which is highly efficient for its intended purpose.

Having thus described my invention, I claim:

1. The method of making a tube comprising taking a tube, expanding one end portion of the tube and decreasing the wall thickness of the one end portion of the tube, causing an intermediate portion of the tube to expand in diameter and limiting the amount of diametrical expansion of the intermediate portion of the tube so that it is of less diameter than that of the one end portion of the tube, causing the other end portion of the tube to expand more than said intermediate portion expands while limiting the amount of expansion of said other end portion of the tube and thereafter reducing the external diameter of each end portion of the tube to equal the external diameter of the intermediate portion of the tube.

2. The method of making a tube comprising taking a tube, expanding one end portion of the tube and decreasing the wall thickness of the one end portion of the tube, holding the one end portion of the tube against axial movement, causing

an intermediate portion of the tube to expand in diameter and limiting the amount of diametrical expansion of the intermediate portion of the tube so that it is of less diameter than that of the one end portion of the tube, causing the other end portion of the tube to expand while limiting the amount of expansion of said other end portion of the tube and thereafter reducing the external diameter of the one end portion of the tube to equal the external diameter of the intermediate portion of the tube.

3. The method of making a tube comprising taking a tube which is of substantial uniform diameter and substantial uniform wall thickness throughout, expanding one end portion of the tube and decreasing the wall thickness of the one end portion of the tube, holding the one end portion of the tube against axial movement, causing an intermediate portion of the tube to expand in diameter while limiting the amount of diametrical expansion of the intermediate portion of the tube so that it is of less diameter than that of the

one end portion of the tube, causing the other end portion of the tube to expand more than said intermediate portion expands while limiting the amount of expansion of said other end portion of the tube and thereafter reducing the external diameter of each end portion of the tube to equal the external diameter of the intermediate portion of the tube.

4. The method of making a tube comprising taking a tube, holding the tube against axial movement, causing one portion of the tube to expand in diameter while limiting the amount of diametrical expansion of the one portion of the tube, causing another portion of the tube to expand more than said one portion expands while limiting the amount of expansion of said other portion of the tube, and thereafter reducing the external diameter of said other portion of the tube to equal the external diameter of the one portion of the tube.

GEORGE E. BARNHART.
